UNITED STATES PATENT OFFICE.

LORNE M. YORK, OF DETROIT, MICHIGAN.

AUXILIARY AIR-INLET DEVICE.

1,250,409.

Specification of Letters Patent. Patented Dec. 18, 1917.

Application filed February 19, 1917. Serial No. 149,589.

To all whom it may concern:

Be it known that I, LORNE M. YORK, a citizen of the United States of America, residing at Detroit, in the county of Wayne 5 and State of Michigan, have invented certain new and useful Improvements in Auxiliary Air-Inlet Devices, of which the following is a specification, reference being had therein to the accompanying drawings.

10 This invention relates to an auxiliary air inlet device for internal combustion engines and has special reference to those engines forming part of the power plants of automobiles.

15 The primary object of my invention is to provide an auxiliary air inlet device that can be readily interposed between a carburetor and an intake manifold without any changes or alterations of either structure, to admit 20 air to the conduits leading from the carburetor to the engine, after the engine has reached a predetermined speed.

Another object of my invention is to provide an adjustable member that can be arranged in a manifold connection to be actuated at a predetermined time, by the gas passing through the connection and this member is articulated with air intake valves so that air will be admitted to the manifold connection after the gas passing there-through has reached a predetermined velocity.

A further object of my invention is to accomplish the above result by a durable and 25 inexpensive mechanical construction to be hereinafter specifically described and then claimed, and reference will now be had to the drawing, wherein

Figure 1 is a cross sectional view of an auxiliary air inlet device interposed between a carburetor and a manifold connection;

Fig. 2 is a plan of the device;

Fig. 3 is a cross sectional view of the 45 same;

Fig. 4 is a cross sectional view of a portion of the device illustrating a slight modification of the invention, and

Fig. 5 is a plan of the same.

50 The device comprises a flat member 1 having opposed apertured ears 2 so that it may be interposed between a carburetor 3 and a manifold connection 4, as shown in Fig. 1, and held in position by bolts 5, nuts 6 or 55 similar fastening means.

The flat member 1 has a central opening 7 corresponding in diameter to the bore or conduit of the manifold connection 4, and arranged in the opening 7 is a reticulated member 8 preferably in the form of a woven wire screen of fine mesh having the marginal edges thereof bound by rings or a binder.

The member 1, in a plane at right angles to the plane of the apertured lugs 2, has the outer side walls thereof recessed, as at 9, 65 and communicating with the inner side walls or opening 7 of the member are air intake openings 10. Pivotaly mounted in the recesses 9 by pins 11 or other pivotal means are flap valves 12 adapted to close the outer 70 ends of the air intake openings 10. The inner sides of said valves are provided with rods 13 extending through the openings 10 and said rods terminate in yokes 14 embracing the screen 8 at opposed sides thereof. 75 The yokes 14 loosely support the screen 8, so that when said screen is raised the valves 12 will be opened, and thereby admit air to the openings 10 and the opening 7 above the screen 8. The opening movement of the 80 valves 12 is limited by the inner ends of the rods engaging the walls of the openings 10. It is very essential for good results, that the air be admitted at some point above the screen 8 or between said screen and the cylinders of an internal combustion engine although a certain degree of efficiency is attained by admitting air below the screen.

The weight of the screen 8 is sufficient to maintain the air valves 12 normally closed 90 and said screen is designed to permit fuel or gas to pass therethrough for starting an internal combustion engine, or reaching a predetermined speed, for instance five miles per hour on the part of an automobile 95 equipped with the device. At approximately five miles per hour the gas drawn into the cylinders of an internal combustion engine has not reached a velocity which will affect the position of the screen 8, but when 100 the speed of the engine is increased and also the velocity of gas or fuel, the screen 8 will tend to temporarily retard or baffle the supply of gas or fuel, and consequently will be raised or adjusted thereby. Such movement 105 on the part of the screen 8 causes the valves 12 to open and admit air above the screen to commingle with the fuel or gas and thus increase the volume of fuel to the cylinders of the engine.

The valves 12 are free to open when actuated by the screen 8, and as heretofore stated, said screen retains the valves normally closed, but in Figs. 4 and 5 of the drawing, there is shown an air valve 13 adapted to be opened by a screen 16 and held normally closed by a spring 17. The spring 17 constitutes means for maintaining the valves closed until gas or fuel reaches a predetermined velocity, and the tension of the spring may be made such that the valve will only be actuated when desired.

The device has been illustrated as used in a horizontal position and as interposed between the carburetor and a manifold connection, but it is to be understood that the device may be used in a vertical position or at any desired angle and is not necessarily limited to a position in proximity to a carburetor, as it may be embodied directly in a manifold or at any point between the carburetor and the cylinders of the engine.

While in the drawings there are illustrated the preferred embodiments of my invention, it is to be understood that the structural elements are susceptible to such variations and modifications as fall within the scope of the appended claims.

What I claim is:—

- 30 1. A device of the type described comprising a member adapted to be interposed between a carburetor and a manifold connection, opposed flap valves supported by said member and adapted for admitting air to the manifold connection, rods carried by the flaps of said valves and extending into said member, and a flat screen in said member supported by said rods and adapted for opening said valves.
- 35 2. A device of the type described comprising a flat member adapted to be interposed between a carburetor and a manifold connection, opposed air valves carried by the outer edges of said flat member adapted for admitting air to said manifold connection, and rigid means in said flat member loosely articulated at its periphery with said air valves and adapted to be actuated by the velocity of fuel drawn into said manifold connection to open said air valves.

ing a flat member adapted to be interposed between a carburetor and a manifold connection, opposed air valves carried by the outer edges of said flat member adapted for admitting air to said manifold connection, 45 and rigid means in said flat member loosely articulated at its periphery with said air valves and adapted to be actuated by the velocity of fuel drawn into said manifold connection to open said air valves. 50

3. A device of the type described comprising a flat member adapted to be interposed between a carburetor and a manifold connection, air valves carried by said flat member outside of said manifold connection adapted for admitting air to the manifold connection, rods carried by said air valves, and extending into said member, and a flat screen solely supported by the rods of said air valves and maintaining said valves normally closed and adapted to be actuated by the velocity of fuel passing into said manifold connection to open said air valves and admit air to said manifold connection above said screen. 55

4. A device of the type described, comprising a flat member having openings, air valves carried by said member at the outer ends of said openings, a flat screen in said flat member, and means carried by said air valves and supporting said screen at the periphery thereof and adjacent said openings so that movement of said screen opens and closes said air valves. 60

In testimony whereof I affix my signature in presence of two witnesses.

LORNE M. YORK.
